[57] ABSTRACT

A horizontal table film editing machine having a plurality of film carrying plates mounted on vertical-axis spindles powered by individual torquemotors; plate, guide roller, sprocket, picture head, and sound head locations define a plurality of film tracks, with provision for increasing in two stages the number of tracks; parallel-spaced film runs, equal-distance-related from the heads, provide for synchronizing by matching of frames anywhere along the length of the runs; a two-motor film transport provides for driving plural picture tracks and plural sound tracks simultaneously at sound speed, synchronized, or at variable speeds synchronized or unsynchronized, with independent interlocks and forward and reverse capability without unthreading, and with constant tension automatic film-wind feed and take-up.

HORIZONTAL FILM EDITING TABLE

This invention relates generally to film editing machines, and particularly to such machines having horizontal tables mounting plural vertical axis spindles handling wound film resting on rotating plate supports.

Film editing is the foundation of the art of making motion pictures. Everything in cinema includes a visual statement resulting from an assembly of images, and scenes of varying length, not usually photographed in correct chronological order or correct length, and comprises a major part in the language of the cinema. Film editing therefore is cutting and splicing strips of film in the sequence and time best adapted to unfold the action in correlation with sounds employed.

In the history of film editing machines the so-called vertical machines requiring film to be mounted on reels having horizontal spindles appeared first, with only one picture-track or one-picture and one-sound track capability. Such machines were noisy, and mechanically cumbersome, with reels driven by long sewing-machine type round-section leather belts, intermittent cams and other mechanisms which tended to tear film and sprocket holes. Shots or scenes from other rolls of film or sound film had to be found by handling those other rolls on other machines or by hand before transfer to the main machine on which gradually the finished product was built up. The horizontal-concept editing machines having plates mounted on vertical axis with multiple roll film handling are recent products, mostly imported and relatively expensive with complicated mechanical and electrical servo motors and banks of relay switches.

A large part of the expense has derived from the approaches taken to meet the considerable requisites of modern film editing machines generally, which ideally include the following:

--the film image area edited must emerge unblemished by the editing apparatus;

--plural picture tracks and plural sound tracks must be available for single or simultaneous use, sound-speed synchronized or variable speed synchronized or unsynchronized, with independent interlocks and forward and reverse capability without unthreading, and with constant tension automatic-film wind feed, and take-up;

--silent winding tapered-thickness, open-face plates must be provided, with all film runs visible and accessible throughout; and with independent brake and stop facility;

--synchronous direct viewing of erect images projected on a screen or screens and manual drive or "inching," capability on individual or interlocked tracks for frame-to-frame examination of picture and sound films must be available;

--broad work areas with direct-view fiducial or synchronization marks are requisite.

A principal object of the present invention is to provide a horizontal multiple-track film editor which has an improved, simplified drive system and track interlocking system co-acting with other structure of relatively conventional design to make available the above advantages.

Other objects and advantages of the invention will become more readily apparent on examination of the following description, including the drawings in which like reference numerals indicate like parts:

FIGS. 1, 2 and 3 are isometric schematic views of three film editor embodiments according to this invention;

FIG. 4 is a plan diagram of the table top of the embodiment of FIG. 3;

FIG. 5 is an isometric exploded view of a plate mounting;

FIG. 6 is an isometric detail of optical elements;

FIG. 7 is a side elevation diagram of a transport mechanism;

FIG. 8 is an isometric view of a portion of the transport mechanism of FIG. 7;

FIG. 9 is a plan diagram similar to that of FIG. 4; and

15 FIG. 10 is an electrical diagram.

The first three Figures illustrate the versatility of the basic layout which permits the simplest four-plate version to be expanded, by addition of units, to six-plate and to eight-plate versions.

20 FIG. 1 illustrates an embodiment 10a of the invention having four plates and two tracks, showing the general relation of the parts in the simplest embodiment. Table 20 has legs 22 and top 24 with spaced struts 26 mounting a shelf 28 above the rear edge. The table top preferably mounts all components except the system amplifier 30, counter 32, and speaker 34 which are on the shelf. All components not needed for moment-to-moment film editing operations are mounted beneath the table top. Mounted on the table top for instant, complete access with elements passing downward through the table top are:

- (a) The optical system 36;
- (b) The picture track I;
- (c) The sound track II; and
- (d) The control panel 38.

Arrangement of the plate assemblies 40 on the table and of the picture and sound film runs according to the present invention is based on a rectangular grid arrangement in which the left and the right edge areas of the table have each three plate-positions in a row equi-spaced on a line parallel with the ends of the table, designatable from front to black L1, L2 and L3 on the left, and R1, R2 and R3 on the right. In addition, the left side has a second row designatable from front to back L4, L5 and L6.

In the four-plate two-track embodiment of FIG. 1 the picture plates are installed at L5, R3 and the sound plates at L2, R2.

50 Synchronizing marks 42, 44 are straight lines parallel with the ends of the table in the left and right middle areas. The parallel runs of picture film P and sound film S perpendicular to the synchronizing marks have equal distance runs from the respective picture and sound heads to the mark and can be synchronously marked or keyed easily by customary means, anywhere along the length of the parallel runs.

FIG. 2 illustrates embodiment 10b, the six plate embodiment having one picture track I and two sound tracks, II and III, is achieved by adding sound plates at the L1 R1 positions, with guide rollers defining a parallel run as described above.

FIG. 3 illustrates progressive expansion through the previous embodiments to an eight plate embodiment 10c having two picture and two sound tracks as more particularly detailed in the next Figure.

FIG. 4 illustrates in diagrammatic form the FIG. 3 table top showing the provision of picture plates at po-

sitions L3, L6 respectively with a double-back picture track IV and an optical system 36' identical to the first mounted in parallel with the first, side-by-side to the left. The double-back portion of the picture track passes on the front, back and right sides of a portion of the second optical system as will be seen.

Reading from front to back the parallel runs are thus second track, first sound track, first picture track, second picture track; making the task of remembering the correlation very easy, the first tracks (first sound, first picture) being the inner ones and the second tracks (second sound, second picture) the outer ones.

Optionally an optical reader 46 can be installed and a third sound head can be installed at 48" in Track IV, if desired, so that the table can be operated as one-picture three sound.

In detail, as to the layout of the basic eight-plate, two picture-track, two sound-track table illustrated, tracks III and II, the sound tracks normally employed, extend the length of the table, from plate assemblies 40 to L1 to R1, and L2 and R2 respectively. One picture track, Track I, extends generally parallel with the sound tracks and almost the length of the table, going from a plate at L5 to a plate at R3.

Projection of the optical axis of optical system 36, associated with track I, extends through the centerlines of sound heads 48" and 48 of tracks II and III respectively.

The distance to the left synchronizing mark 42 from the optical centerline project along each film path is made equal, and similarly the distances to the right synchronizing mark are made equal, by disposition of the guide rollers 52 and drive sprockets 54; 42 equates to 44 for track IV.

The optical system 36' of track IV is parallel-spaced from the track I optical system, and track IV loops from plate position L3 around a portion of the optical system (the portion being described later, in reference to FIG. 6) to plate positon L6, producing by means of guide rollers a film run perpendicular to synchronizing mark 42 and around the looped portion to the actual optical axis of optical system 36' measuring the same distance as the other film runs measure to the optical axis projected of optical system 36.

FIG. 5 diagrams the arrangement of a typical plate assembly 40. Each plate 56 is perforate, has a collar 58 attached, and is tapered in section to a thin edge by a top bevel according to best currently known practice, providing the positive, quiet, non-scraping feed and take up important for editing. A torquemotor 60 mounted to the underside of the table as by screws 62 in tapped holes 64, with the shaft 66 mounting a hub 68 in turn having a shaft 70 protruding upwardly through a hole in the table, rotatively mounts each plate. Each torquemotor has a conventional electromagnetic brake 72 for stopping and or locking the shaft and plate when desired.

The torquemotors serve to rotate the plates in take up and to retard them when paying out, by an arrangement disclosed later in reference to the drive generally. Voltage can be varied at will on each pair of the torquemotors as will be seen, greatly adding to the flexibility and versatility of the editing table in use.

FIG. 6 diagrams the relation of the parts of the optical system 36.

Source 74 attached beneath the table top projects a beam upward through a table aperture and through

lens 76 onto diagonal reflector 78, through to a focal point at film F, through a rotating prism 80, a focussing lens assembly 82, through a dove prism 84 held at 45° rotational angle by bracket 86 to achieve proper image erection, onto reflector system 88 in picture head 90 and then onto screen 92 for viewing.

The rotating prism is operated in synchronism with the passing film by means described in reference to the following two Figures.

FIG. 7 diagrams the elements and inter-connections of the transport mechanism of the eight-plate embodiment of the invention, 10c of FIG. 3.

FIG. 8 correspondingly illustrates portions of the transport mechanism of the eight-plate embodiment 10c.

FIGS. 7 and 8 are therefore described together.

The main drive is divided vertically into upper transport section 91 and lower transport section 93 and horizontally into a main frame assembly or transport proper 94, attached below the table top with elements protruding upwardly through the table top, and to auxiliary frame assemblies 96, 98, 100, similarly attached with elements protruding upwardly also.

Main frame assembly 94 comprises a vertical backing plate 102 with four horizontal crossplates 104, 106, 108, 110, fixed in parallel-spaced relation from top to bottom.

Three similar vertical shaft assemblies 112 (Track III, 114 (Track II), 116 (Track I), are carried by the main frame parallel-spaced in a row with a portion of each protruding upwardly through clearance in the table top. Each protrusion terminates at the top in a knurled inching knob 118, and carries immediately below that one of the three drive sprockets 54 for the respective tracks.

Below the table each shaft passes through a bearing 120 in the top crossplate of the frame and a co-axially aligned bearing 122 in the second crossplate of the frame. Between these first two crossplates each shaft carries an electromagnetic brake rotor 124; the rotors are paired with brake stators 126 fixed to the upper crossplates.

Between the second and third crossplates each of the shafts terminates in an electro-magnetic clutch motor 128. The corresponding magnetic clutch stator 130 for each is fixed on the end of one of shafts 132, 134, 136, mounted in respective co-axiality with the first described shafts, with each journaled in aligned bearings 137 and 139 in the third and fourth crossplates from the top.

Shafts 134 and 136 bear at the lower ends interbearing connected magnetic clutch halves 138, 138', fixed to them and associated respective magnetic clutch halves 140, 140', freely rotative on the shafts and respectively having affixed to them chain sprockets 142 and 143.

Reversible synchronous motor 144 bolted vertically to the backing plate with the motorshaft extending downwardly, connects with the chain sprocket on the lower end of shaft 136 through endless chain 146 and sprocket 148 on the motor-shaft.

In similar manner, reversible variable speed motor 150 bolted to the backing plate with the motorshaft down, connects with the chain sprocket on the lower end of shaft 134 through endless chain 152 and sprocket 154 on the motor-shaft.

Thus the three co-axial shaft assemblies are basically identical except that shaft assembly 112 is shorter than shaft assemblies 114 and 116 and has at the bottom no clutched motor-connection.

A fourth shaft assembly 156 (Track IV) basically identical to shaft assembly 112 is bolted beneath the table top by means of auxiliary frame assembly 98, similar to frame assembly 94, some distance away from the other shafts and is permanently connected with shaft 136 by means of respective sprockets 158, 160 on the shafts and by chain 162. Shaft assembly 156 has a brake assembly 176, 178, and a clutch connection 180, 182 to a lower shaft 184, in similar manner to shaft assembly 112.

Shaft 134 is permanently connected to shaft 136 by chain 164 on sprockets 166 and 168 respectively, and shaft 132 is permanently connected to shaft 134 by means of sprockets 170 and 172 fixed on the respective shafts and chain 174.

Through this arrangement and interlock of the motor switches either motor 144 or 150 can drive but not both simultaneously, and the drive turns all four shafts 132, 134, 136, 184 regardless of which motor is employed.

Rotating prisms 80, 80' are driven from shaft assemblies 96 and 100 respectively when the appropriate clutches are engaged by means of gear sets 186, 188 and 190, 192 affixed to the respective shaft assemblies 156, 100 and 116, 96.

A further feature apparent in the Figures under consideration is the mechanical counter 194, optionally drivable through the table top by means of counter shaft 196 gear set 198, 200, sprockets 199 and chain 201 on the shaft and countershaft.

The foolproof versatility of this arrangement will become easily apparent upon inspection of the diagrammatic Figure when taken into consideration with the reversible, variable torquemotor feature on each plate and the intertrack permutations to be explained later. At this point, it is sufficient to note that none, all, or any partial combination of the upper shafts or output shafts for Tracks I, II, III and IV can be operated together at synchronous speed or variable speed or can be freewheeled by the inching knobs or held locked in position by suitable conventional operation of the clutches, brakes, the torquemotors, and the torquemotor brakes, but that track-to-track synchronism can never be accidentally lost while the sprockets drive the film.

FIG. 9 illustrates the versatility of plate-to-plate winding of film F. Literally every plate can be operatively connected with every other plate in film winding, in many cases without intervening roller guides. Additionally, A to B winding, in which film is rewound to put the emulsion side in or out on the spool as desired, is possible in most cases.

FIG. 10 schematically diagrams the electrical hookup of the components of the system.

The dotted lines A, B, define a circuit for one track. The circuits for the other tracks are similar. All circuit components are conventionally wired for the functions, as indicated.

Main switch 202 controls the main power supply (120VAC) to the system and components. A manually variable transformer 204 regulates voltage supplied to all feed torque motors 60 and associated plate assemblies. A second and similar manually variable trans-

former 204' regulates voltage supplied to all take up torque motors 60' and plate assemblies. The variable voltage provides selective torque for optimum winding and tensioning. With the transport drive in use, moderate drag on the feed assembly and positive wind on the take up plate assembly assure trouble free film winding.

A double-pole double-throw center-off switch 206, 206' activates and conventionally reverses by lead reversal each of the torquemotors when desired. A single-pole double-throw center-off track-interlocking switch 208 supplies 90 VDC from DC power supply 224 to small holding brake 124/126 keep the associated film drive sprocket from moving or creeping when not being driven by a transport motor 144, 150 or by a torque motor.

Hand-inching or "framing" or sound-film aligning or "synch" adjustments may be made while small holding-brake 124/126 is energized.

20 The "off" position frees the upper drive shaft and sprocket, permitting the torquemotors to power-wind the film in either direction.

25 The interlocking position energizes electromagnetic transport clutch coupling 128/130, which interlocking function can be accomplished while the lower transport system (93, FIG. 7) is running, or while stopped. The operator may interlock any track or combination of tracks in the transport system to achieve synchronous driving of those tracks interlocked. Tracks may also be driven interlocked at variable speed using motor 150 which may advantageously be an AC/DC series wound worm-gear-head motor. As indicated then, the transport may be run at sound speed or at variable speed or stopped at will.

30 Gang switch 210a, 210b, may advantageously be a three-position rotary switch with three taps on each of two decks, as indicated.

The middle positon holds whatever torque-tension voltage on the feed and take-up plate assemblies with established by the setting of variable transformers 204, 204'.

35 The left hand positon applies 120VAC across the feed motor 60 and keeps back-tension "normal" on the take-up plate assembly through the torquemotor 60' circuit variable transformer 204, causing a reverse power-wind of the film to the feed plate.

40 The right hand position applies 120VAC across the take-up torquemotor 60' and transformer voltage across the feed torque motor 60, causing a power wind of the film in the opposite direction, to the take-up plate.

45 These provisions provide for each track a high speed forward- and reverse-winding capability, when not on interlock to the synchronous or variable speed motors, which provide slower winding speeds.

50 Double-pole double-throw switch 212a, 212b, in the right hand position supplies energy through switch 210a, 210b the rotary switch, and activates the functions determined by the position of the rotary switch. In the lefthand position of switch 212a, 212b, the rotary switch is de-energized, and the electromagnetic brakes 72, 72' are energized (90VDC, 212b, from DC power supply 224) on each of the feed and take-up torque motors and associated plate assemblies, causing the film to stop.

55 Switch 214 selects synchronous speed or variable speed for the transport drive by supplying 90VDC from

the DC power supply to the appropriate clutch (138/140 for the sound speed motor, 138'/140' for the variable speed motor.)

Although both the variable speed and the synchronous or sound speed motors may be turned on at the same time, both clutches cannot be engaged at the same time because alternative poles of the same switch, 214, control them.

Single-pole triple-throw center-off switch 216 turns on, turns off, and reverses, in that order, the synchronous or sound speed motor 144. Reversal is conventional, by shifting the winding leads.

Double-pole double-throw center-off switch 218, turns on, turns off and reverses, in that order, the variable speed motor 150. Reversal is conventionally through lead reversal; series-connected foot pedal 220, which may advantageously be a conventional carbon-rod type, regulates the speed.

Fuses 222 are preferably used to protect against overloads, and a pilot lamp 226 is desirable to indicate system activation.

The lamp circuits are conventional and not shown.

It can be seen that the vertical backing plate and cantilevered crossplates of the film transport, although surprisingly rigidly holding the upper and lower spindles rigidly aligned with themselves and the coupling, and holding the several spindles on it in serial, parallel-spaced relation to close tolerances, gives open access for attachment of wiring to the commercially available electromagnetic components (which have the usual internal slippings) and to the motors, as well as giving adjustment and inspection access to all the other components of the film transport section.

Obviously many modifications and variations of the present invention are possible in light of the above teachings. It is, therefore, to be understood that within the scope of the appended claims the invention may be practiced otherwise than as specifically described.

What is claimed and desired to be secured by United States Letters Patent is:

1. A film editing machine comprising: a film transport, including: a plurality of spindle assemblies, means rotatably supporting said plurality of spindle assemblies vertically oriented in series-parallel-spaced relation, each spindle assembly including an upper spindle and a lower spindle co-axially aligned therewith, means for selectively retarding rotation of each of said upper spindles, means for releasably connecting each upper spindle with the respective lower spindle co-axially aligned therewith, means for coupling in rotation all said lower spindles, a synchronous speed motor, means for releasably connecting the synchronous speed motor with a first said lower spindle, a variable speed motor, means for releasably connecting the variable speed motor with a second said lower spindle; means for manually grasping each of said upper spindles, and a film sprocket proximately below each said grasping means.

2. A film editing machine as recited in claim 1, and additionally: means for defining respective film tracks associated with plural of said respective film sprockets, including first and second plates for each film track, means for rotating all said plates about parallel-spaced vertical axes, a plurality of roller guides, means for visually indicating synchronization of film when in plural of said tracks; an optical system including a prism, means for rotating the prism about a vertical axis in

synchronism with rotation of one of said upper spindles, a light beam source positioned for projecting a light beam through a film in a first said film track and thence through said prism, a picture head positioned for receiving and displaying said light beam; a sound head assembly positioned for association with a second film track, means responsive to the sound head; a horizontal table, and means for supporting said film transport below the horizontal table with the sprockets thereof and all said plates, roller guides, visual indicating means, optical system, and sound head assembly in substantially horizontal relation above said horizontal table.

3. A film editing machine as recited in claim 2, wherein the means rotatably supporting said plurality of spindle assemblies comprises a vertical backing plate with a plurality of horizontal crossplates fixed in cantilevered, parallel-spaced relation from top-to-bottom thereon, with said plurality of spindle assemblies passing through the horizontal cross-plates.

4. A film transport as recited in claim 3, wherein first and second of said crossplate mount at the top of the backing plate the means rotatably supporting the upper spindles, wherein third and fourth of said crossplates therebelow mount the means rotably supporting the lower spindles, wherein the means for selectively retarding each of said upper spindles said first and second crossplates, wherein the means for releasably connecting each upper spindle with the respective lower spindle co-axially aligned therewith comprises a respective electromagnetic coupling located between the second and third of said crossplates, wherein the means for coupling in rotation all said lower spindles comprise a plurality of respective endless chain members engaging sprockets on the respective lower spindles between the third and fourth of said crossplates, and wherein the means for releasably connecting said motors with respective said lower spindles comprise an electromagnetic clutch on each respective lower spindle below the fourth of said crossplates.

5. A film editing machine as recited in claim 4, wherein the table has left and right edges, each having three plate positions in a row equi-spaced on a line parallel with the ends of the table, designatable from front to back L1, L2 and L3 on the left and R1, R2 and R3 on the right, wherein the left edge has a second row of plate positions designatable L4, L5 and L6 from front to back, thereby forming a rectangular grid of three rows of parallel spaced plate positions, wherein the series of spindles is fixed to the table in a front-to-back direction, wherein the optical system is located on a back portion of the table with the direction of light beam projection parallel with the row of spindles, wherein the sound head is located forwardly of and in alignment with the optical system; wherein said first and second plates of a first film track, are located at positions L5 and R3 respectively, with said first film track passing through a portion of the optical system and through a position for film engagement with the sprocket of the rearmost spindle assembly.

6. A film editing machine as recited in claim 5, wherein first and second plates of a second film track are located at positions L2 and R2 respectively, with said second film track passing through a portion of said sound head assembly and through a position for film engagement with the sprocket of a spindle assembly

proximately forward of the rearmost spindle assembly.

7. A film editing machine as recited in claim 6, wherein a portion of the first track and a portion of the second film track are parallel-spaced from each other and from an edge of the table, wherein the means for visually indicating synchronization is fixed in perpendicular relation across all said film track parallel portions, and wherein the distance from the means for visually indicating synchronization along the first said film track to an operative portion of the optical system is equal to the distance along said film track to an operative portion of the sound head assembly.

8. A film editing machine as recited in claim 7, wherein a second sound head assembly is provided forward of and in fore-and-aft alignment with the first said sound head assembly, wherein first and second plates of a third film track are located at positions L1 and R1 respectively, with said third film track passing through a portion of said sound head assembly and through a position for film engagement with the sprocket of a spindle assembly proximately forward of the second said spindle assembly.

9. A film editing machine as recited in claim 7, wherein second portions of all said first and second film tracks are parallel-spaced from each other and from said edge of the table, wherein a second means for visually indicating synchronization is fixed in perpendicular relation across all said second portions of said film tracks, wherein the distance from the means for visually indicating synchronization along the respective said film track to said respective operative portions is equal, and where the second means for visually indicating synchronization is on a side of said operative por-

tions opposite to that of the first said means for visually indicating synchronization.

10. A film editing machine as recited in claim 8, wherein a portion of the third film track is parallel-spaced from the parallel-spaced portions of the first and second film track, and wherein the distance from the means for visually indicating synchronization along the third film track to an operative portion of the second sound head assembly is equal to the distance therefrom along the second film track to an operative portion of the first sound head.

11. A film transport as recited in claim 10, wherein an auxiliary frame assembly is provided having thereon an additional said spindle assembly and sprocket located lateral to and similar in construction to each of the aforesaid spindle assemblies, and similarly affixed in relation to said horizontal table; wherein a second prism is provided, the second prism having means for rotating the prism about a vertical axis in synchronism with rotation of upper spindle of the additional spindle assembly on the auxiliary frame, and means coupling in rotation the lower spindle of said additional spindle assembly with a lower spindle of the first said plurality of spindle assemblies.

12. A film transport as recited in claim 11, wherein a second said picture head is provided proximately lateral of the first said picture head, wherein first and second plates of a fourth film track are located at positions L3 and L6, respectively, with said fourth film track doubling-back around and through a portion of the optical system and through a position for film engagement with the sprocket of said spindle assembly.
